UNITED STATES PATENT OFFICE.

WILLIAM JESSIE LAMAR, OF KANSAS CITY, MISSOURI, ASSIGNOR OF ONE-HALF TO
JOHN S. KIRKPATRICK, OF KANSAS CITY, MISSOURI.

AUTOMATIC INJECTOR FOR BOILERS.

1,023,110.

Specification of Letters Patent.

Patented Apr. 9, 1912.

Application filed January 26, 1911. Serial No. 604,918.

To all whom it may concern:

Be it known that I, WILLIAM JESSIE LAMAR, of the city of Kansas City, in the county of Jackson, in the State of Missouri, 5 have devised a new and useful Invention in the Way of Automatic Injectors for Boilers.

My invention relates to an automatic injector for boilers, and my object is to provide a novel apparatus of this character 10 whereby water may be maintained at a predetermined level in stationary or portable boilers, without attention on the part of an engineer or fireman.

In order that the invention may be fully 15 understood, reference will now be made to the accompanying drawing, in which:

Figure 1 shows a broken side elevation of a locomotive and tender, provided with the improved apparatus forming my invention. Fig. 2 is an enlarged broken side elevation of the apparatus, partly in section. Fig. 3 is a vertical section of the upper portion of the locomotive boiler, and an automatic float-valve employed in carrying out 25 the invention, and Fig. 4 is a section of a valve used in carrying out the invention.

In carrying out the invention, I employ an automatic valve comprising a float 1, a valve-plug 2, and a shell having a seat 4, 30 against which the upper tapered end of the valve-plug 2 is adapted to abut. Float 1 is preferably made of asbestos reinforced with sheet-metal, to withstand the heat and pressure to which it is subjected. Valve-plug 35 2 is held in axial alinement with seat 4 by a guide secured to an interior portion of the boiler.

5 designates a steam-pipe communicating with the shell of the automatic valve, just 40 described, and leading to a steam-chest 6, containing a reciprocable piston 7, operably connected to an annulus 8, provided for the purpose of simultaneously actuating valves 10, 12 and 14.

45 9 designates an injector, which receives its supply of water from the tender 19 of the locomotive through a feed-pipe 15, and a supply of steam from the upper portion of the boiler through a pipe 11 to force the water received through pipe 15, into the boiler through a discharge-pipe 13.

The flow of steam through pipe 11 is controlled by valve 10, the flow of steam and water through discharge-pipe 13 is controlled by valve 12, and the flow of feed-

water through pipe 15 is controlled by valve 14 and a valve 18, which latter is located adjacent the tender 19, and actuated by the annulus 8, through the intermediacy of a connecting-rod 16, provided with a turn-buckle 17, whereby said rod may be lengthened or shortened as desired.

When the water in the boiler falls below a predetermined level, either through leakage or evaporation, float 1 falls therewith and carries valve-plug 2 away from its seat 4. This opens communication between pipe 5 and the boiler, so that steam from the latter is free to flow through the former to the steam-chest 6, where it impinges against piston 7 and forces the same forward. As piston 7 moves forward, it turns the annulus 8, which in turn, through the intermediacy of its connections with valves 10, 12, 14 and 18, opens said valves, permitting steam to flow into the injector 9 through pipe 11 and suck feed water from the tender through pipe 15, and force it into the boiler through pipe 13, until the level of the water in said boiler is restored to normal. When this occurs, float 1, which moves upward with the water, forces valve-plug 2 against its seat 4, and thus cuts off further supply of steam from the boiler to the steam-chest 6. Thus relieved of the pressure of the steam, piston 7 is drawn backward by suction of the vacuum created in steam-chest 6 on the forward movement of piston 7. As piston 7 moves backward, it turns the annulus 8 to normal position, causing it to close valves 10, 12, 14 and 18, and stopping the operation of the injector until the water in the boiler is again reduced below normal level when the foregoing operation is repeated.

Fig. 4 shows a vertical section of valve 12, 95 which is identical in construction to valves 10, 14 and 18. Said valve consists of a casing *a* in which is mounted a valve-plug *e*, having a port *c* extending therethrough of the same cross sectional area as the pipe 100 communicating with the opposite sides of shell *a*, so that the flow of fluid through said port, when registering with the pipe, will be unobstructed, as is the case in valves wherein the port is of less diameter than the 105 pipe communicating therewith. Valve-plug *e* is held from vertical movement by a jam-nut *b*, which engages the conical upper portion of said valve-plug and also the internally threaded upper portion of casing 110

a, and is provided with a cap-nut *h*. The jam-nut *b* is assisted in holding the valve-plug *e* from vertical movement by a stem *d* projecting from the valve-plug through the bottom of casing *a*, and provided with a nut *f*. The upper portion of the valve-plug *e* is provided with a stem *i* extending through cap-nut *h* and provided with a lever *j* adapted to be actuated by the annulus *g*.

10 From the foregoing description, it will be understood that I have produced an apparatus whereby water may be automatically maintained at substantially a predetermined level in a boiler, without attention on the part of an attendant. This insures the best results, as it is obvious that the cubic steam space of the boiler is maintained substantially uniform at all times, and by having the water gradually fed to 20 the boiler as required, the water in the boiler will be kept substantially at uniform temperature, and evaporation thereof into steam, will also be substantially uniform. The evil effects is overcome, of injecting 25 large quantities of water into the boiler at one time, which usually occurs when the injector is manually operated, instead of automatically operated, as in the present case, and a maximum head of dry steam of uniform pressure is maintained at a minimum 30 consumption of fuel.

Having thus described my invention, what I claim, and desire to secure by Letters Patent, is:

35 1. In combination with a boiler, an injector, a discharge pipe leading from said injector into the boiler, a feed-water pipe communicating with said injector, a pipe containing fluid under pressure communicating with the injector to force the feed-water into the boiler, valves on said pipes, an annulus adapted to partially rotate and simultaneously actuate said valves, and means controlled by the water level in the 40 boiler to actuate said annulus.

45 2. In combination with a boiler, an injector, a discharge pipe leading from said injector into the boiler, a feed-water pipe communicating with said injector, a pipe containing fluid under pressure communicating with the injector to force the feed-water into the boiler, valves on said pipes, an annulus for simultaneously actuating 50 said valves, and a fluid controlled piston for actuating said annulus.

55 3. In combination with a boiler, an injector discharging into said boiler, a feed-water pipe communicating with said injector, two valves to control the flow of water 60 through said feed-water pipe, an annulus having direct connection with one of said valves, a connecting-rod connecting said annulus with the other valve, a steam supply

pipe leading from the boiler to the injector, a valve to control the flow of steam through 65 said steam-pipe and connected to the annulus, and means controlled by the water in the boiler to actuate said annulus.

4. In combination with a boiler, an injector discharging into said boiler, a feed-water-pipe leading to said injector, a valve to control the flow of water through said feed-water pipe, a steam-pipe leading from the boiler to the injector, a valve to control the flow of steam through said steam-pipe, 70 an annulus operably-connected to said valves to simultaneously actuate the same, a piston operably-connected to said annulus to partially rotate the same, a cylinder inclosing said piston, a steam-pipe leading 75 to said cylinder from the boiler, a shell within the boiler communicating with the inlet end of the last-mentioned steam-pipe, and provided with a valve seat, a vertically-arranged valve-plug adapted to engage said 80 seat, and a float controlled by the water level in the boiler to actuate said valve-plug.

5. In combination with a locomotive, a tender therefor, an injector mounted upon 90 said locomotive, a feed-water pipe leading from the tender to said injector, a valve adjacent the tender to control the flow of water through said feed-water pipe, a valve adjacent the injector to control the flow of 95 water through said feed-water pipe, a steam pipe leading from the locomotive boiler to the injector, a valve to control the flow of steam through said steam-pipe, a discharge pipe leading from the injector to the boiler, a valve to control the flow of fluid through 100 said discharge-pipe, an annulus adjacent the injector and operably-connected to the feed-water pipe valve, the steam-pipe valve, and the discharge-pipe valve adjacent said 105 injector to actuate the same, a connecting-rod connecting the annulus and the feed-water pipe valve adjacent the tender, a reciprocable piston to partially rotate the annulus, a cylinder containing said piston, a steam-pipe leading from the boiler to said cylinder, a valve seat within the boiler communicating with said steam-pipe, a valve-plug adapted to engage said seat, a guide for said valve-plug to hold it in proper relation to its seat, and a float controlled by 110 the water level in the boiler to actuate said valve plug, substantially as set forth and described.

In testimony whereof I hereunto affix my 120 signature in the presence of two witnesses.

WILLIAM JESSIE LAMAR.
